INVENTOR.

UNITED STATES PATENT OFFICE

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY

PNEUMATIC HAMMER

Application filed October 1, 1926. Serial No. 138,862.

This invention relates to fluid pressure percussive tools and more specifically to large pneumatic hammers used in demolition work as in cutting off bolt and rivet heads. Such tools are commonly referred to as rivet cutting guns and usually require on account of their size and weight at least two men to operate, one to direct the demolishing end of the gun and the other to control the motive fluid.

Tools of the type described strike a single blow in one position of the throttle handle which must then be moved to a different position to return the hammer piston for the next blow. In order that the blow may be delivered with full force it is the usual practice to provide a large permanently open vent port in the cylinder wall about an inch back of the piston when the latter is in its impacting position. This open vent necessitates the use of a large amount of motive fluid to return the piston, so that such tools are costly to operate in the matter of air consumption.

One object of the present invention is to devise a tool of the described type which requires but little motive fluid for the back stroke of the piston without interfering with a free forward or power stroke. Another object is to make the tool of simple design in order to keep its cost within practical limits. Other objects will be apparent from the detailed description which follows.

In order to illustrate the invention one concrete embodiment thereof is shown in the accompanying drawings in which:

Fig. 1 is a side elevational view, partly in section, of an improved form of rivet cutting gun;

Fig. 2 is a view similar to Fig. 1 showing the operative parts in different positions.

The tool shown comprises a cylinder 3 having secured thereto a front head 4 receiving the shank end 5 of the working tool and a back head 6 having a transverse bore receiving the control valve 7 arranged to be manually operated by a handle 8. Valve 7 controls admission and exhaust ports for the motive fluid to effect the reciprocations within cylinder 3 of the hammer piston 9, which

imparts its blow to the working tool 5 and which is arranged to be cushioned on its rearward stroke by a spring 10. A pressure fluid supply pipe 11 attached to back head 6 supplies motive fluid to valve 7 through a port 12. Back head 6 also provides a large exhaust port 13, a small exhaust port 14, a large port 15 opening into the rear end of the piston chamber, and a small port 16 connected to front head 4 by a flexible conductor or pipe 17 which communicates with a passage 18 opening into auxiliary valve chamber 19. A cup valve 20 having a small port 21 therethrough is arranged for limited reciprocatory movement in chamber 19 which chamber is closed at its outer end by a screw plug 22 having a projection 22^a serving as a stop for valve 20. The forward end of the valve chamber has an annular series of vent ports 23 controlled by a valve 20 and the valve chamber communicates with the front end of the piston chamber by a port 24.

The operation of the tool is as follows: With the parts in the position shown in Fig. 1 piston 9 is on its rearward stroke. A flat 7^a on valve 7 establishes communication between supply port 12 and port 16, thereby directing motive fluid into valve chamber 19 moving valve 20 to the position shown (if not already in this position), the pressure fluid passing in limited amount through valve port 21 into the forward end of the piston chamber to drive piston 9 rearwardly. Passage 18 being larger than port 21 insures a greater pressure in the valve chamber 19 than in the piston chamber so that valve 20 is retained in the position shown. The rearward end of the piston chamber is meantime open to exhaust by reason of groove 7^b in valve 7 establishing connection between ports 15 and 13. To reverse the movement of the piston valve handle 8 is moved to the forward position shown in Fig. 2 whereupon ports 12 and 15 are connected by a transverse bore 7^c in valve 7, thereby directing motive fluid in full volume and pressure behind piston 9. At the same time flat 7^a establishes connection between ports 16 and 14 so that connection 17 is open to exhaust thereby vent-

ing auxiliary valve chamber 19 and permitting valve 20 to be moved outwardly by the air in advance of piston 9 to uncover exhaust ports 23. The piston is thus able to deliver its blow with full force and entirely without back pressure.

It will be noted that when auxiliary valve 20 moves to its outward position shown in Fig. 2 stop 22^a closes port 21 and in addition prevents the valve from entirely closing off passage 18, so that when the control valve handle 8 is again returned to the position shown in Fig. 1 the motive fluid admitted through connection 17 to passage 18 has access behind the valve 20 to move it to the position shown in Fig. 1. The sealing of port 21 by stop 22^a is important since it prevents initial escape of pressure fluid directed to the auxiliary valve chamber thereby using the full power of the fluid to overcome inertia and friction as well as the tendency of the valve to stick. Thus movement of valve 20 is insured even if control handle 8 is moved slowly in the rearward direction. If the tool is not to be operated while connected to a source of fluid supply the control handle is moved to neutral position midway between the positions shown in Figs. 1 and 2.

From the above it will be apparent that the exhaust ports 23 at the forward end of the piston chamber permit free exhaust of the air in advance of the piston on the latter's working stroke, that on the return stroke of the piston exhaust ports 23 are closed by the movement of auxiliary valve 20 produced by the motive fluid admitted by the main control valve for the rearward stroke of the piston so that only a small amount of motive fluid is required for this purpose, and that the parts producing the new operative arrangement are simple, inexpensive to manufacture and assemble and well able to withstand the hard usage to which such tools are subjected without getting out of order.

While a preferred form of the invention has been herein shown and described, it is to be understood that the invention is not limited to the specific details thereof but covers all changes, modifications and adaptations within the scope of the appended claims.

I claim as my invention:

1. A fluid pressure hammer comprising a cylinder providing a piston chamber, a piston reciprocable therein, a valve, ports and passages directly controlled by said valve for supplying pressure fluid to and venting it from the rear end of said piston chamber, a vent port for the front end of the piston chamber, and an auxiliary valve controlling said vent port and arranged to admit motive fluid released by said first named valve to the piston chamber for the rearward stroke of the piston.

2. A fluid pressure hammer comprising a cylinder providing a piston chamber, a pis-

ton reciprocable therein, a valve, ports and passages directly controlled by said valve for supplying pressure fluid to and venting it from the rear end of said piston chamber, a vent port for the front end of the piston chamber, and an auxiliary valve controlling said vent port and having an end wall with a port therethrough for admitting motive fluid in a limited amount to the piston chamber to effect the rearward stroke of the piston.

3. A fluid pressure hammer comprising a cylinder providing a piston chamber, a piston reciprocable therein, a manually operable valve arranged directly to control the supply of pressure fluid to and the venting of it from the rear end of the piston chamber, and an auxiliary valve controlling a vent for the front end of the piston chamber and providing a single port of restricted size to admit motive fluid to the piston chamber to effect the rearward stroke of the piston.

4. A fluid pressure hammer comprising a cylinder providing a piston chamber, a piston reciprocable therein, a manually operable valve for controlling the movements of the piston, a valve chamber adjacent the forward end of said cylinder connecting with the piston chamber and having a vent port for the latter, a conduit extending to said valve chamber under control of said valve, and an auxiliary valve in said chamber for controlling said vent port, said auxiliary valve being moved to cover said port by pressure fluid admitted to the valve chamber by said conduit and being moved to uncover said port by the air in advance of the piston on its working stroke.

5. A fluid pressure hammer comprising a cylinder providing a piston chamber, a piston reciprocable therein, a manually operable valve for controlling the movements of the piston, a valve chamber adjacent the forward end of said cylinder connecting with the piston chamber and having a vent port for the latter, a conduit extending to said valve chamber under control of said valve, and an auxiliary valve in said chamber for controlling said vent port, said auxiliary valve being moved to cover said port by pressure fluid admitted to the valve chamber by said conduit and being moved to uncover said port by the air in advance of the piston on its working stroke, said auxiliary valve being arranged to admit to the piston chamber to effect the rearward stroke of the piston a portion of the motive fluid entering said valve chamber.

6. A fluid pressure hammer comprising a cylinder providing a piston chamber, a piston reciprocable therein, a manually operable valve for controlling the movements of the piston, a valve chamber adjacent the forward end of said cylinder connecting with the piston chamber and having a vent port for the latter, a conduit extending to said valve chamber under control of said valve, and an

auxiliary valve in said chamber for controlling said vent port, said auxiliary valve being moved to cover said port by pressure fluid admitted to the valve chamber by said conduit and being moved to uncover said port by the air in advance of the piston on its working stroke, said auxiliary valve having a restricted port for admitting to the piston chamber a portion of the motive fluid entering said valve chamber.

7. A fluid pressure hammer comprising a cylinder providing a piston chamber, a piston reciprocable therein, a manually operable valve at the rearward end of said cylinder for controlling the movements of the piston, a valve chamber opening into the forward end of said piston chamber, a passage leading to said valve chamber under control of said valve, a cup valve movable in said valve chamber, vent ports for the piston chamber controlled by said cup valve, said cup valve having a port establishing connection between said valve chamber and the piston chamber, said valve port being smaller than the passage leading to said valve chamber to retain a predominating pressure in said valve chamber.

8. A fluid pressure hammer comprising a cylinder providing a piston chamber, a piston reciprocable therein, a manually operable valve for controlling the movements of the piston, an open-ended valve chamber communicating with the forward end of the piston chamber, a closure for the outer end of said valve chamber, a passage leading to said chamber under control of said valve, said valve chamber having vent ports for the piston chamber, an auxiliary valve in said valve chamber controlling said vent ports, said auxiliary valve having a port therethrough and a stop on said closure for limiting the movement of said auxiliary valve in one direction and for controlling said last named port.

45 9. A fluid pressure hammer comprising a cylinder providing a piston chamber, a piston reciprocable therein, a manually operable valve for controlling the movements of the piston, an open-ended valve chamber communicating with the forward end of the piston chamber, a closure for the outer end of said valve chamber, a passage leading to said chamber under control of said valve, said valve chamber having vent ports for the piston chamber, an auxiliary valve cylindrical in shape reciprocable in said valve chamber to control said vent ports, said auxiliary valve having a transverse wall with a single port therethrough arranged to communicate with the piston chamber, said port being of less cross sectional area than said passage.

10. A fluid pressure hammer comprising a cylinder providing a piston chamber, a piston reciprocable therein, a manually operable valve for controlling the movements of the

piston, an open-ended valve chamber communicating with the forward end of the piston chamber, a closure for the outer end of said valve chamber, a passage leading to said chamber under control of said valve, said valve chamber having vent ports for the piston chamber, an auxiliary valve cylindrical in shape reciprocable in said valve chamber to control said vent ports, said auxiliary valve having a transverse wall with a port therethrough, and a stop on said closure arranged to engage said valve to limit its movement in one direction and to close said port.

11. A fluid pressure hammer comprising a cylinder providing a piston chamber, a piston reciprocable therein, a manually operable valve for controlling the movements of the piston, an open-ended valve chamber communicating with the forward end of the piston chamber, a closure for the outer end of said valve chamber, a passage leading to said chamber under control of said valve, said valve chamber having vent ports for the piston chamber, a cup valve reciprocable in said valve chamber to control said vent ports and having a port therethrough, and a stop on said closure for engagement with said cup valve to prevent closing of said passage by said cup valve and for controlling said last named port.

12. A fluid pressure hammer comprising a cylinder providing a piston chamber, a back head secured to said cylinder, a manually operable valve in said head for controlling the movements of the piston, a front head on said cylinder, an open-ended valve chamber in said front head opening into the piston chamber, a conduit under control of said valve leading to said valve chamber, vent ports for the piston chamber opening into said valve chamber, a cup valve within said valve chamber controlling said vent ports and arranged to be thrown to cover said vent ports by motive fluid admitted by said conduit and in the other direction to uncover said vent ports by air in advance of the piston on its working stroke, a port in said cup valve of less area in cross section than the area of said conduit for directing a portion of the motive fluid from said conduit into said piston chamber to drive the piston on its rearward or non-working stroke, a closure plug for the outer end of said valve chamber, and a projection on said plug forming a stop to engage said cup valve and prevent it from closing said conduit when the valve moves to open said vent ports.

Signed by me at Detroit, in the county of Wayne, and State of Michigan, this 27th day of September, 1926.

EDWARD W. STEVENS.
